FACSIMILE SYSTEM

Henry Shore, Elizabeth, N. J., assignor to Radio Corporation of America, a corporation of Delaware

Application January 28, 1933, Serial No. 654,088

3 Claims. (Cl. 178—69.5)

The present invention relates to facsimile systems and is directed primarily to arrangements which will tend to eliminate the streaked or ripple effects present in many reproduced pictures.

Such ripples or streaks usually appear as parallel lines of alternate light and dark shades running in the direction of the line advance. These ripples and streaks are usually caused by uneven gears and uneven driving speeds of the facsimile or picture transmission and reproduction gear.

It is one of the primary objects of the present invention to avoid such streaked effects, which is done by providing ways and means by which the picture carrying drum or other appropriate instrumentality may be driven at a more uniform speed during the scanning operation for transmission or the reproduction operation for reception.

Other objects of the invention are to provide for improved quality of the reproduced picture.

Still other objects of the invention are to provide ways and means by which this improved quality may be obtainable and still not depart materially from the general form of transmitting and receiving apparatus now in use, and as an example of which reference may be made for mechanical construction to United States Patent No. 1,803,133, and for electrical construction and operation to copending application Serial No. 558,750 filed August 22, 1931 jointly by Henry Shore and James N. Whitaker, assigned to Radio Corporation of America.

Another object of the invention is to provide a mechanical filter system which will tend to make the picture transmission and reproduction more uniform. In addition, it is an object of this invention to provide a mechanical filter system which can readily be attached to present existing picture apparatus. The cut-off frequency of such a mechanical filtering system is so chosen that it will be below any frequency which will tend to introduce ripples into the drum speed.

Other objects and advantages of the invention, of course, will become apparent and suggest themselves to those skilled in the art to which the invention is directed by reading the following specification and claims in connection with the accompanying drawing, wherein:

Fig. 1 represents conventionally a line diagram of the constituent parts of a picture transmitting or reproducing system; and wherein

Figs. 2, 3 and 4 illustrate further details of the mechanical filter system connected intermediate the driving motor and the picture carrying drum.

Of these figures, Fig. 2 illustrates a sectional view of the mechanical filter system; Fig. 3 is a somewhat detailed view showing the arrangement of the braking instrumentality used in connection with the mechanical filter system; and Fig. 4 illustrates more particularly the resilient coupling between the driving and driven members.

To make reference now to the accompanying drawing, it is already known that substantially any picture transmitting and receiving apparatus embodies a scanning drum upon which the picture of which the electro-optical or other type of image representation is desired is suitably supported or upon which the image representation is produced on a suitably supported recording surface. The scanning drum of either the transmitting or receiving apparatus is driven by some appropriate form of drive means suitably controlled as to speed in accordance with the desired rate of transmission. The varying intensities of light and shadow of the picture or subject to be transmitted are tested or analyzed by way of a scanning device. The resulting signals are then transmitted to receiving points by way of a transmitter and amplifier device. The signals transmitted are then suitably received and amplified and caused to influence a reproducing device to produce a duplicate of the subject or picture located at the point of transmission.

Such apparatus is conventionally shown in Fig. 1 wherein the driving motor is designated as 1 and is arranged to drive the scanning drum 3 through an appropriate mechanical filter device 5. Where desired, and as shown by Patent No. 1,803,133 above mentioned, there may be a speed changing gear box 4 intermediate the driving and driven members.

The record surface (not shown) supported by the scanning drum is suitably analyzed or tested by the scanning device 7 and varying light values thereof are converted in well known manner into electrical impulses to influence the transmitter amplifier 9 from which the signals are directed to a transmitting device 11 and suitably transmitted to various points of reception by way of the antenna system 13 or, where desired, by any appropriate form of wire line connecting device. If the device is used for receiving pictures, or signals representing other types of subjects, signals are suitably received at 13 and passed through the receiving device 11 and thence through the reproducer amplifier to produce from the reproducing device 1 appropriate signals to control the

image reproduction upon a surface carried upon the scanning drum 3.

The mechanical filter device 5 applicable for use either in connection with the transmitting device or receiving device is shown in more particular detail in Figs. 2, 3 and 4 and it is to this arrangement and its cooperative use in connection with the driving and driven means 1 and 3 of either the transmitter or the receiver devices to which this invention is particularly directed.

In apparatus used up to the present time, the elimination of the ripple effects above explained has been attempted by the use of high precision mechanical work. This mechanical high precision work has been made possible by forming the gears very accurately and also by providing very small clearances and careful alignment of the bearing surfaces, all of which are held to extremely close tolerances. This work, however, has called for a great degree of mechanical skill and consequently the cost of such precision work has been found to be considerably greater than is justified by the amount of ripple or picture streak elimination accomplished, because even with the finest mechanical layout the ripple is present in the reproduced record at least to some degree.

Therefore, the present system to provide ripple elimination makes use of relatively simple mechanical filter devices which can be applied to a machine which is not absolutely mechanically perfect from a precision viewpoint and yet this relatively simple filter device is capable of eliminating the ripple or streaked effect in the reproduced record entirely. Naturally, this results in a large saving in installation costs, since the filter can be applied to machines already installed at relatively low cost, and since it is not necessary to provide for such a high degree of accuracy in the mechanical work new apparatus will not have to be designed to meet such rigid mechanical specifications.

In its broadest sense the mechanical filter corresponds substantially to an electrical filter comprising series inductance (L), a terminating resistance (R) and shunt capacity (C). The mechanical filter is so constructed and arranged, as will become more apparent from the following description, that the resilient connection to the driving member 1 corresponds to the capacity of the electrical filter, the flywheel combination, to be hereinafter described, corresponds to the inductance of the electrical filter, and the braking means, also to be later described in detail, corresponds to the terminating resistance, so that, where it is assumed that this filtering arrangement is to replace, in effect in a mechanical system an electrical half section filter in an electrical circuit, the formula

$$R = \sqrt{\frac{L}{C}}$$

for an electrical circuit will hold true. In the mechanical filter R represents the braking force, L the mass, that is, the flywheel, and C the resilient drive member of the system. From this it can be seen that if the proper resistance or braking force is not applied hunting or oscillations will result.

So constituted, the mechanical filter comprises a flywheel 21, a braking device, generally designated 23, and a resilient drive means, generally designated 25. The driving motor 1 is arranged so as to connect with the shaft 27 which, in turn, has attached thereto by means of a pin 29 an

appropriate disk member 31. The disk 31 is provided at opposite edges with slotted portions 33 and at points on its periphery angularly spaced by a slight amount diametrically opposite pins 35. Upon each pin 35 is attached a spring member 37 which connects, in turn, to a fastening point 39 upon the flywheel 21 so that when the shaft 27 is rotated the driving force is applied through disk member 31 connected to the shaft by way of the pin 29 so as to rotate in a resilient manner the flywheel in the direction shown by the arrow. Also provided on the face of the flywheel adjacent the disk member 31 are pins 40 which are positioned with the slotted portions 33 but free from the edges thereof. The pins 40 have provided upon the outer surface thereof coverings in the form of cushioning pieces 41, such as rubber or equivalent, so as to absorb any possible shock due to a sudden pull exerted upon the flywheel due to rotation of the shaft 27 member 21.

From this description it is seen that as the shaft 27 is rotated the flywheel 21 will also be rotated through the resilient coupling device coupling the flywheel with the shaft. The flywheel itself is rigidly connected to the shaft member 43 which connects with the picture carrying or scanning drum 3 by means of a key or pin 45 so that as the flywheel is rotated due to rotation of the driving motor the scanning drum will also be rotated through the resilient or yieldable connection between the drive motor and the flywheel.

Under such conditions it will be obvious that the mass of the flywheel will to a considerable extent cause the picture carrying or scanning drum 3 to rotate at uniform speed even in spite of slight hunting in the driving motor 1. However, it has been found that this mass is in itself insufficient to provide for absolutely smooth and even rotation of the scanning drum since, as was above explained in connection with the formula defined, it is possible for hunting to occur in the absence of any critical damping in the system. This damping effect is herein provided for mechanically in much the same manner as the damping resistance of the electrical filter circuit.

This resistance or damping is provided according to the present disclosed arrangement by way of a braking device, generally designated 23. The supporting means for the brake 23 is in a supporting bracket 49 suitably mounted and carried from a support member 51 in which the shaft 27 is suitably journaled in bearings 53 in the same manner that the shaft 43 is journaled in the bearings 55 carried by a support member 57 intermediate the flywheel and the scanning drum 3. Upon the support member 49 there is suitably mounted by way of guide members 59 a brake shoe 61 sliding within the support member which is provided with a felt or other suitable covering or lining 63 adapted to bear upon the surface of the flywheel member 21. The guide members 59 are supported at their upper end, that is, the end opposite the end at which the brake shoe 61 is supported, in a support member or brake tensioning yoke member 65. Passing through the center of the brake tensioning yoke 65 is a screw threaded spindle 67 to the upper end of which is attached a knurled thumb nut 69 so that in accordance with the position of the thumb nut 69 the brake tensioning yoke is moved either upwardly or downwardly to cause the brake shoe and the brake lining 61 and 63 to bear with greater or lesser

force upon the flywheel surface and thus to exert greater or lesser braking force.

In order to provide a finer degree of adjustment there is provided intermediate the thumb nut 69 and the brake tensioning yoke member 65 a suitable tension spring member 71 which serves to regulate and maintain uniform tension upon the brake. It is this spring member, in combination with the brake, which corresponds to the resistance of the electrical filter circuit, and it is by virtue of the adjustment and the pressure at which the brake shoe rests upon the flywheel surface that the damping of the system is altered.

To define to a still further degree the operation of this filter system, the device may be classified as a low pass filter. Normally, under ideal conditions, the motor will rotate at uniform velocity. An ideal type of gear box, such as the speed control gear box 4, would, of course, transmit this velocity to the scanning drum 3 uniformly. However, due to mechanical imperfections in the motor and gear box there will be superimposed upon the uniform velocity higher velocities which would normally be transmitted to the drum. Any variation in acceleration appears as a ripple in the finished or reproduced picture or other subject.

The use of the resilient coupling and flywheel combination, which constitutes the low pass filter, prevents these higher velocities from being transmitted. This fact is evident because any sudden acceleration simply causes the spring member of the mechanical filter system to be placed in tension and so stretched, if the acceleration is positive, or compressed if the acceleration is negative. The combined moment of inertia of the flywheel and the scanning drum resists any tendency for the velocity to change. Consequently, the superimposed velocities will be reduced in this combination. To eliminate completely the transmission of these higher velocities the flywheel and drum must be suitably damped or there is a slight tendency for the system to oscillate at its natural period, as would be true in the electrical circuit, were it not for the damping resistance above described. This damping, therefore, is effected in the mechanical filter by means of the braking device and since the spring member provided with the braking device is adjustable the exact value of the damping can be achieved empirically. The flywheel is usually an essential element in the combination since the moment of inertia of the scanning drum alone is ordinarily not sufficient to provide a suitable cut-off frequency.

It should be understood that this invention is not limited to a single section low pass filter device since a multi-section filter may prove desirable where the undesired velocities are very high. The multi-section filter may be provided by the addition of one or more flywheels and springs. For a two section filter the first flywheel is mounted on the shaft free to turn, while the second is keyed to the shaft. The second spring is used to couple from the first to the second flywheel. In general, a multi-section filter will not be necessary.

Also, where a small flywheel does not serve to eliminate completely the ripple, a flywheel of increased moment of inertia will accomplish the desired object in much the same manner as the change in the electrical constituents of the electrical filter will change the characteristics thereof.

While the invention has herein been described in connection with one of the preferred embodiments which it may assume, it is nevertheless to be understood that it is capable of considerable modification both in form and arrangement of parts, and that such modifications may be made without departing from the spirit and scope as herein set forth.

Having thus described my invention, what I claim and desire to secure by Letters Patent is the following:

1. In combination, a driving element, a driven element and a mechanical filter system connecting the driving and driven elements, said filter system comprising a flywheel rigidly connected with the driven element and resiliently connected with the driving element, and a variable mechanically operable means to critically damp the mechanical filter system.

2. In combination, a driving element, a driven element, a flywheel rigidly connected with the driven means, a resilient connection between the flywheel and the driving means so as to drive the driven element through the flywheel connection, and a variable tension brake arranged to bear upon the flywheel surface so as to critically damp the system.

3. A filter system comprising a driven member, a flywheel rigidly attached to the driven member, a driving means resiliently connected with the flywheel so as to drive thereby the driven member, and a variable mechanical braking means to critically damp the flywheel to reduce thereby hunting in the system.

HENRY SHORE.
